Primary Examiner — Ruth McInroy(74) *Attorney, Agent, or Firm* — Lerner, David, Littenberg, Krumholz & Mentlik, LLP(57) **CLAIM**

The ornamental design for a dust collecting barrel, as shown and described.

DESCRIPTION

FIG. 1 is a perspective view of a dust collecting barrel showing my new design;

FIG. 2 is a front view thereof;

FIG. 3 is a back view thereof;

FIG. 4 is a left side view thereof;

FIG. 5 is a right side view thereof; and,

FIG. 6 is a top view thereof.

The environmental details shown in broken lines form no part of the claimed design.
